Attoys.

UNITED STATES PATENT OFFICE.

HOLLIS H. SAWYER, OF NEWTON, MASSACHUSETTS.

POSITIONING MEANS FOR VERTICALLY-ARRANGED ARTICLES.

1,215,720.

Specification of Letters Patent.

Patented Feb. 13, 1917.

Application filed April 22, 1916. Serial No. 92,977.

To all whom it may concern:

Be it known that I, HOLLIS H. SAWYER, a citizen of the United States, and a resident of Newton, in the county of Middlesex and State of Massachusetts, have invented an Improvement in Positioning Means for Vertically-Arranged Articles, of which the following description, in connection with the accompanying drawings, is a specification, like characters on the drawings representing like parts.

This invention relates to means for controlling the position of articles which are kept or stored in a vertical position; such for example as index cards, letter folders, etc., in the so-called vertical files. The object of my invention is to regulate the arrangement of the articles so that they will not only present a more orderly appearance and will also be more readily handled by the user so that a considerable saving of time will result.

My invention will best be understood by reference to the following description taken in connection with the accompanying drawing showing an illustrative form of my device and wherein:

Figure 1 is a side view of a file drawer embodying my invention;

Fig. 2 is a cross section thereof. In both Figs. 1 and 2 the proportion of parts has been somewhat exaggerated for clearness; and

Fig. 3 is a part perspective, part section of a member used in the construction shown in Figs. 1 and 2.

Referring to Fig. 1, I have there shown as an example of my invention a record holder in the form of a drawer 1 of well known form adapted to receive snugly letter folders or other records 2 which are set therein on edge. The drawer 1 may be provided with the usual movable back piece 3 which may be shifted to vary the effective depth of the drawer to accommodate fewer or more folders 3 and hold them approximately vertical.

In the use of filing devices such as described, it is necessary to allow the records to have some freedom of movement in the drawer 1 to permit them to be given a rearwardly slanting position that facilitates the examination of matter on their faces. As the file is moved about, as, for example, when the drawer is drawn in and out, the records will continue to move on their own

inertia after the holder itself stops. The result of this movement of the records has been that they have assumed a forwardly sloping position with their faces hidden. It is then very inconvenient to examine some record in the file and, if a back 3 is used, the temptation exists to release it to give room to tilt backward the row of records behind the one to be examined. To do so, however, only aggravates the defect until the file becomes vertical chiefly in name. My invention provides means to prevent this undesirable forward sloping of the records. I also am able to utilize the forces that produce it in the ordinary file to obtain the opposite and desirable result of giving the records a rearward slant.

I attain this result by providing means for impeding what I may call spontaneous movement of the bottoms of the folders in the holder, that is, movement not deliberately given them by some person. Preferably also I permit movement of the upper parts of the records so that they may swing where held and assume a proper slant. For this purpose I may construct the surface of the holder at or near the bottom thereof to present projections 4 of low height relatively to the dimensions of the records themselves and engaging the lower portions thereof.

In the embodiment of my invention chosen for illustration, I have formed these projections 4 as suitable lugs (see Fig. 3) secured at intervals to strips 5 of light metal, preferably pierced as at 6 to receive fastening devices. One or more of these strips, two being shown in Fig. 2, may be secured longitudinally on the bottom of the holder 1 or on the sides near the bottom. The form and size of these projections may be widely varied, but I have obtained good results from lugs one sixteenth of an inch high, one quarter of an inch wide and spaced about three inches apart. For clearness in illustration the size of the projections has been exaggerated in Figs. 1 and 2, and I preferably would make them relatively smaller in practice. I prefer to make the projections quite small as the records can then be readily moved backward and forward in the holder when it is desired to do so either by pushing them past the projections or lifting them very slightly. My device is thus sharply distinguished from those employing partitions which subdivide the

holder. I retain the freedom for adjustment of the ordinary form of file and attain control of the records without sacrifice of filing space and without hindrance to expansion or contraction of the volume of records filed.

Of the exact nature of the physical forces involved in my invention I am not fully advised and therefore I shall not attempt to explain the precise theory of action. Tests have shown, however, that not only are the records prevented from falling forward with their faces down because the movement of their lower parts rearwardly in the holder is impeded, but that they develop a swinging movement pivoting about the bottom edges, and automatically assume a rearward slant in the best position for examination by the user of the file. The result is a file more orderly in appearance and wherein the records are so much more accessible that much time is saved the user.

I have described in considerable detail the embodiment of my invention illustrated but, while the form shown is a practicably desirable one and readily adapted for the reconstruction of files as now made, it will be understood that it is exemplary merely and that different kinds of attachment may be used or that the material of the bottom or sides of the holder may be so fashioned as to give the desired impediment to the movement of the letter folders or other records.

Copies of this patent may be obtained for five cents each, by addressing the "Commissioner of Patents, Washington, D. C."

Furthermore, evidently the form of holder is not of the essence of the invention and my invention may be usefully applied in various situations where articles are kept in an upright position.

What I do claim and desire to secure by Letters Patent is:

1. A receptacle for holding vertical records, the bottom of which presents a series of projections of relatively low height formed to project between the records and spaced to receive a number of records between adjacent projections whereby spontaneous movement in the receptacle of the lower parts of the records is prevented.
2. A receptacle for holding vertical records having narrow strips therein secured longitudinally thereto, said strips having projections of relatively low height formed to project between the records and spaced along the strips to receive records between adjacent projections.
3. As a new article of manufacture a metal strip having provision for securing the same longitudinally in a receptacle for vertical records and having projections of low height spaced therealong.

In testimony whereof I have signed my name to this specification.

HOLLIS H. SAWYER.

Witness:

ROBERT H. KAMMLER.
